UNITED STATES PATENT OFFICE.

GEORGE P. WIGGINTON, OF KALAMAZOO, MICHIGAN, ASSIGNOR TO KALAMAZOO
LOOSE LEAF BINDER COMPANY, OF KALAMAZOO, MICHIGAN.

LOOSE-SHEET DEVICE.

1,395,754.

Specification of Letters Patent.

Patented Nov. 1, 1921.

Application filed May 14, 1920. Serial No. 381,313.

To all whom it may concern:

Be it known that I, GEORGE P. WIGGINTON, a citizen of the United States, residing at Kalamazoo, county of Kalamazoo, State 5 of Michigan, have invented certain new and useful Improvements in Loose-Sheet Devices, of which the following is a specification.

This invention relates to improvements in 10 loose sheet devices.

My improvements are especially designed by me for the handling of loose sheets in accounting or record systems.

The main objects of this invention are:

15 First, to provide an improved loose sheet device which facilitates the handling or manipulation of sheets in the making of entries or records thereon and also which provides means for securely holding them in 20 a book or binder for filing and for reference purposes.

Second, to provide a loose sheet device having these advantages which is very convenient to use and at the same time simple 25 and economical in structure.

Further, and objects relating to structural details will definitely appear from the detailed description to follow.

I accomplish the objects of my invention 30 by the devices and means described in the following specification. The invention is clearly defined and pointed out in the claims.

A structure which is a preferred embodiment of my invention is clearly illustrated 35 in the accompanying drawing forming a part of this specification, in which:

Figure I is a perspective view showing the sheets arranged in a binder for filing or reference purposes.

40 Fig. I^A is a detail section on a line corresponding to line 1^A—1^A of Fig. I, showing structural details of the binder.

Fig. II is a perspective view of the sheet body removed from the binder but still retained or bound by the posts.

Fig. III is a perspective view of the sheets arranged on the support with the posts remaining in the sheet body.

Fig. IV is a perspective view of the support partially broken away showing the holes in the side members through which the

posts inserted in the sheet body from the under side thereof may be removed.

Fig. V is an inverted detail view of the support. 55

Fig. VI is a detail section on a line 6—6 of Fig. III, the posts being shown in full lines.

Fig. VII is a detail plan view showing the manner of offsetting the sheets, the sheet 60 guide member of the support being indicated by dotted lines.

Fig. VIII is a detail perspective view showing a portion of the sheets in each 65 holder with a part of the sheets in the receiving holder offset.

Fig. IX is a detail perspective view of the sheet body with part of the sheets offset and the binding posts inserted for placing in 70 the binder.

Fig. X is a detail section of a modified 75 form of binder embodying the features of my invention.

In the drawing similar reference characters refer to similar parts throughout the several views, and the sectional views are taken looking in the direction of the little arrows at the ends of the section lines.

Referring to the drawing, the sheets 1 are 80 provided with holes 2 and notches 3 at their binding edges. The purpose of the holes and notches will be made clear as the description proceeds. I provide a binder consisting of covers 4 having clamping members 5 pivotally connected thereto and binding 85 members 6 extending between the clamping members. These clamping members are clamped by the binding members upon the sheets, the mechanism by which this is accomplished being preferably that shown in the patent to Bushong No. 914,383, March 9, 1909, and as such mechanism forms no part 90 of this invention, it is not illustrated or described herein.

The notches 3 are spaced so as to receive 95 the binding members 6. The posts 7 are inserted in the holes 2 of the sheets, the posts illustrated being of the sectional type so that they may be lengthened or shortened to accommodate the sheet body. The posts are 100 provided with disk-like heads 8 which engage the outer sheets, and are inserted from

both sides of the sheet body constituting binding members adapted to hold the sheets together as a unit, as shown in Fig. II.

The posts have studs or projecting parts 9 at their outer ends adapted to engage the holes 10 provided therefor in the clamping bars so that when the clamping bars are adjusted to the posts, the sheet body is secured or retained in the binder and at the same time when the clamping bars are separated, the sheet body is freed and may be removed from the binder as a unit as shown in Fig. II.

To facilitate the handling of sheets when removed from the binder, I provide a support designated generally by the numeral 11 and consisting of a pair of holders 12 and 13 each comprising an end member 14 and a side member 15 disposed relative to each other to provide the trough-like holders. The side and end members of the holder 12 are disposed at right angles so that when the sheets are arranged thereon with their ends abutting the end member as shown in Fig. VIII, the sheets are alined to receive the binding posts. To aline the sheets laterally, the holders are provided with guides 14', the guide 14' of the holder 13 being provided mainly to aline the posts with the openings 16 in the holder so that the posts may be withdrawn through these holes—see Fig. VI—while the guide of holder 12 alines the sheets in an alined body or in an offset relation so that selected sheets may be distinguished, for instance, such sheets as have had their accounts effected, and also the sheets are alined so that the posts may be reinserted in the holes 16. The holes and notches are arranged so that there are registering holes and registering notches when in either position.

The posts may be reinserted with the sheets in offset position as shown in Fig. IX, and the sheet body placed in the binder 45 which is provided with covers which are extended so as to protect the sheets so offset, as indicated by dotted lines in Fig. I.

In Fig. X, I illustrate my improvements applied to another type of binder in which the clamping bars 17 are secured to the covers 18 by flexible hinges 19, the clamping bars being connected by posts 20, the details not being shown as they form no part of this invention, and any suitable means for 55 securing the binder members together to coact with the posts 7 being contemplated by me.

My improved loose sheet handling device greatly facilitates the handling of loose 60 sheets for accounting purposes, as the manipulation of the sheets for making entries thereon is made very convenient. Further, the sheets are securely bound for storage and reference purposes when in the binder.

65 I have not attempted to illustrate or de-

scribe other modifications or adaptations which I contemplate as I believe the disclosure made will enable those skilled in the art to which my invention relates to embody or adapt the same as may be desired.

Having thus described my invention, what I claim as new and desire to secure by Letters Patent is:

1. The combination with sheets having notches in their binding edges and holes adjacent their binding edges, the holes and notches being uniformly spaced so that there are registering holes when the sheets are arranged in an alined body or with selected sheets in an offset relation with their notches 75 registering, of a binder comprising a pair of binder members provided with clamping bars having holes in their inner faces, binding members extending between said clamping bars, posts engageable in the holes of 80 said sheets from opposite sides of the sheet body and having heads engaging the sheet body and studs engageable with the holes of said clamping bars, said posts being released from the binder members by the separation of the clamping bars so that the sheet body may be removed from the binder as a unit while held by said posts, and a sheet support comprising a pair of sheet 85 holders having side and end members, one side and end member being disposed at right angles to each other so that the sheets may be arranged on the side member with their binding edges abutting the end member, said 90 end members having guides thereon coacting with the notches of the sheets for alining them on the holders, said side members having holes therein through which posts may be inserted into or removed from the 95 body of sheets.

2. The combination with sheets having notches in their binding edges and holes adjacent their binding edges, of a binder comprising a pair of binder members provided with clamping bars having holes in their inner faces, binding members extending between said clamping bars, posts engageable in the holes of said sheets from opposite sides of the sheet body and having heads engaging the sheet body and studs engageable 115 with the holes of said clamping bars, said posts being released from the binder members by the separation of the clamping bars so that the sheet body may be removed from the binder as a unit while held by said 120 posts, and a sheet support comprising a pair of sheet holders having side and end members, one side and end member being disposed at right angles to each other so that the sheets may be arranged on the side member with their binding edges abutting the end member, said end members having guides thereon coacting with the notches of the sheets for alining them on the holders, 125 said side members having holes therein 130

through which posts may be inserted into or removed from the body of sheets.

3. The combination with sheets having holes adjacent to their binding edges, of a binder comprising a pair of binder members provided with clamping bars having holes in their inner faces, binding members extending between said clamping bars, posts engageable with said sheets from opposite sides of the sheet body and having heads engaging the sheet body and studs engageable with the holes of said clamping bars, said posts being released from the binder members by the separation of the clamping bars so that the sheet body may be removed from the binder as a unit while held by said posts, and a sheet support comprising a pair of sheet holders having side and end members, one side and end member being disposed at right angles to each other so that the sheets may be arranged on the side member with their binding edges abutting the end member, said side members having holes therein through which posts may be inserted into or removed from the body of sheets.

4. The combination with sheets having notches in their binding edges and holes adjacent their binding edges, the holes and notches being uniformly spaced so that there are registering holes when the sheets are arranged in an alined body or with selected sheets in an offset relation with their notches registering, of a binder comprising a pair of binder members, binding members for said binder members, posts engageable in the holes of said sheets from opposite sides of the sheet body and having heads engaging the sheet body and removably engageable with said binder members, and a sheet support comprising a pair of sheet holders having side and end members disposed so that the sheets may be arranged on the side members with their binding edges abutting the end members, said end members having guides thereon coacting with the notches of the sheets for alining them on the holders, said side members having holes therein through which posts may be inserted into or removed from the body of sheets.

5. The combination with sheets having notches in their binding edges and holes adjacent their binding edges, of a binder comprising a pair of binder members, binding members for said binder members, posts engageable in the holes of said sheets from opposite sides of the sheet body and having heads engaging the sheet body and removably engageable with said binder members, and a sheet support comprising a pair of sheet holders having side and end members disposed so that the sheets may be arranged on the side members with their binding edges abutting the end members, said end members having guides thereon coacting with the notches of the sheets for alining them on the

holders, said side members having holes therein through which posts may be inserted into or removed from the body of sheets.

6. The combination with sheets, of a binder comprising a pair of binder members, binding members for said binder members, posts engageable with said sheets from opposite sides of the sheet body and having heads engaging the sheet body and removably engageable with said binder members, and a sheet support comprising a pair of sheet holders having side and end members disposed so that the sheets may be arranged on the side members with their binding edges abutting the end members, said side members having holes therein through which posts may be inserted into or removed from the body of sheets.

7. The combination with sheets, of a binder comprising a pair of binder members, binding members for said binder members, posts engageable with said sheets from opposite sides of the sheet body and having heads engaging the sheet body and removably engageable with said binder members, said posts being released by the separation of the binder members so that the sheet body may be removed from the binder as a unit while held by said posts, and a sheet support comprising a pair of sheet holders having side and end members disposed so that the sheets may be arranged on the side members with their binding edges abutting the end members, said side members having holes therein through which posts may be inserted into or removed from the body of sheets.

8. The combination with sheets having notches in their binding edges and holes adjacent their binding edges, of a binder comprising a pair of binder members provided with clamping bars having holes in their inner faces, binding members extending between said clamping bars, posts engageable with said sheets and binder members, said posts being released from the binder members by the separation of the clamping bars and constituting a binding means for the sheet body so that it may be removed from the binder as a unit, and a sheet support comprising a pair of sheet holders having side and end members disposed so that the sheets may be arranged on the side members with their binding edges abutting the end members and the posts removed from the sheets, said end members having guides thereon coacting with the notches of the sheets for alining them on the holders to receive the posts.

9. The combination with sheets, of a binder comprising a pair of binder members provided with clamping bars having holes in their inner faces, binding members extending between said clamping bars, posts engageable with said sheets and binder members, said posts being released from the

- binder members by the separation of the clamping bars and constituting a binding means for the sheet body so that it may be removed from the binder as a unit, and a sheet support comprising a pair of sheet holders having side and end members disposed so that the sheets may be arranged on the side members with their binding edges abutting the end members and the posts removed from the sheets. 10
10. The combination with sheets having notches in their binding edges and holes adjacent their binding edges, of a binder comprising a pair of binder members having holes therein, posts removably engageable with the holes in said sheets and binder members and constituting a binding means for the sheet body so that it may be removed from the binder as a unit, and a sheet support comprising a pair of sheet holders disposed so that the body of sheets may be arranged on one of the holders and the posts removed from the sheets and the sheets transferred to the other holder which is adapted 15
15. to support the sheets to receive the posts ^{that} the body of sheets held by the posts
- may be replaced in the binder as a unit, said holders having guides thereon coacting with the notches of the sheets for alining them on the holders to receive the posts. 30
11. The combination with sheets, of a binder comprising a pair of binder members, posts removably engageable with said sheets and binder members and constituting a binding means for the sheet body so 35 that it may be removed from the binder as a unit, and a sheet support comprising a pair of sheet holders disposed so that the body of sheets may be arranged on one of the holders and the posts removed from the 40 sheets and the sheets transferred to the other holder which is adapted to aline the sheets to receive the posts so that the body of sheets held by the posts may be replaced in the binder as a unit. 45

In witness whereof I have hereunto set my hand and seal in the presence of two witnesses.

GEORGE P. WIGGINTON. [L. S.]
